Patented Oct. 10, 1967

208,893

COMBINED HAIR LIFTER AND COMB

Daniel A. Mauro, 4657 Malden Drive,
Wilmington, Del. 19803

Filed Sept. 20, 1966, Ser. No. 3,926

Term of patent 14 years

(Cl. D86—8)

FIG. 1 is a side elevational view of a combined hair lifter and comb showing my new design;

FIG. 2 is an end view thereof; and

FIG. 3 is a top plan view.

I claim:

The ornamental design for a combined hair lifter and comb, as shown.
